UNITED STATES PATENT OFFICE.

JACOB PRESS, OF NEW YORK, N. Y.

DESIGN FOR A MAN'S GARTER.

59,566.

Specification for Design.

Patented Nov. 1, 1921.

Application filed July 3, 1920. Serial No. 393,976. Term of patent 14 years.

To all whom it may concern:

Be it known that I, JACOB PRESS, a citizen of Russia, residing in the borough of the Bronx of the city of New York, in the State of New York, have invented a new, original, and ornamental Design for Men's Garters, of which the following is a specification, reference being had to the accompanying drawing, forming a part hereof, in

I claim—

The ornamental design for a man's garter, as shown.

This specification signed this 1st day of July, 1920.

JACOB PRESS.
